IMED Technology Inc., Catheter Securement—IMed316, Jun. 4, 2012, <http://www.imedtechnology.com/html/cath-secure.html>.*Primary Examiner — David Muller*Assistant Examiner* — Nathan Johnston(74) *Attorney, Agent, or Firm* — Stevens & Showalter, LLP(57) **CLAIM**

The ornamental design for a medical line anchor, as shown and described.

DESCRIPTION

FIG. 1 is a perspective view of a medical line anchor showing our new design;

FIG. 2 is a top plan view thereof;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a bottom plan view thereof; and,

FIG. 8 is perspective view similar to FIG. 1, with the transparent cover removed.
